DESIGN FOR A BLOUSE

Irving Geist, New York, N. Y.

Application October 10, 1935, Serial No. 58,928

Term of patent 3½ years

To all whom it may concern:

Be it known that I, Irving Geist, a citizen of the United States of America, residing in Manhattan, county of New York, and State of New York, have invented a new, original, and ornamental Design for a Blouse, of which the following is a specification, reference being had to the accompanying drawing, forming part thereof, wherein,

The parallel lines commencing from the center of the neckline and extending to either side of the waist portion of the blouse, represent superimposed cording.

I claim:

The ornamental design for a blouse, substantially as shown, and described.

IRVING GEIST.
